UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND.

MACHINE GUN.

Application filed January 7, 1921. Serial No. 435,651.

(GRANTED UNDER THE PROVISIONS OF THE ACT OF MARCH 3, 1921, 41 STAT. L. 1313.)

To all whom it may concern:

Be it known that we, ARTHUR TREVOR DAWSON and GEORGE THOMAS BUCKHAM, both subjects of the King of Great Britain, residing at Vickers House, Broadway, Westminster, in the county of London, England, have invented certain new and useful Improvements in or Relating to Machine Guns (for which they have made application in Great Britain September 4, 1919, Pat. No. 165,859), of which the following is a specification.

This invention relates to machine guns, particularly those of the Vickers automatic type.

15 The present invention consists of a machine gun in which there are combined and used together the various devices and mechanism set forth in the specifications of our three British Patents Nos. 165,857, 165,858 20 and 141,605, the essential features comprising the device for retaining the firing spring and the side lever axis pin of the lock in their assembled position as described in the first of our said specifications, the stop-piece 25 for the crank and the resilient bush between the crank-handle roller and the spindle or spigot of this roller as described in the second of our said specifications, and the sear and tumbler arrangement described in the 30 third of our said specifications.

In order that the said invention may be clearly understood and readily carried into effect the same will be described more fully with reference to the accompanying drawings in which:—

Figure 1 is a vertical longitudinal section through the mechanism casing of a Vickers automatic gun provided with the combination of features in accordance with this invention,

Figure 2 is a local side elevation showing the aforesaid crank-handle roller,

Figure 3 is a plan of Figure 1 with the mechanism casing cover removed, Figures 45 4 and 5 are, respectively, a sectional side elevation and a rear elevation showing on a larger scale the lock and the parts carried thereby.

50 A is the mechanism casing, A^x is the crank, A' is the connecting rod pivoted at its rear end to the crank and at its forward end to the socket A^o of the side levers which are pivoted to the lock (the crank, the con-

necting rod and the side levers forming toggle levers as is well understood), A² is the 55 crank shaft, A³ is the crank handle, and A⁴ is the roller with which the tail A^{3x} of this crank handle co-operates. B is the lock casing, B' is the firing pin, B² is the firing spring and B³ is the side lever axis pin. C 60 is the tumbler for cocking the firing pin, C' is the sear and C² is the actuating arm for the sear.

The aforesaid device for retaining the firing spring B² and the side lever axis pin B³ in their assembled position comprises a resilient member having forwardly extending arms D, D which are situated a suitable distance apart so as to fit tightly, by reason of their resiliency, against the sides of the 70 lock casing. The lower forward parts of said arms have curved recesses d which fit in circumferential grooves cut in the axis pin B³. D^x is a bridge-piece connecting the 75 said arms together at the rear and D' is an actuating member which is riveted or otherwise connected to the bridge-piece D^x in front thereof and has two limbs one vertical and depending and the other more or less horizontal and projecting forwards. 80 The latter limb has lateral extensions D², D². (Figure 5) at its forward end adapted to engage in recesses in front of projections b, b on the lock casing. The rear end of the 85 firing spring bears against the aforesaid vertical limb and by the co-operation of the lateral extensions D², D² with the said projections holds the arms D, D in engagement with the circumferential grooves in the axis pin B³. The lower part of the said vertical 90 limb has a dovetail D³ fitted into a correspondingly shaped recess in the lower part of the lock casing so as to prevent the device from moving out of position by a bodily vertical movement during the working of 95 the gun.

To enable the axis B³ and the firing spring B² to be removed, the member D' is rocked against the opposition of the firing spring to disengage the arms D, D from the circumferential grooves in the axis pin and is then after the withdrawal of the axis pin rocked by the spring B² in the reverse direction to disengage the dovetail D³ from its recess; the member D' can then be lifted slightly to 100 disengage the lateral extensions D², D² from 105

the projections b , b and the device is then moved rearwards thus leaving the firing spring free to be removed in a rearward direction. To facilitate the manipulation of 5 the member D' the lower part of its vertical limb is knurled and occupies a readily accessible position at the lower part of the mechanism casing of the gun; this limb is also formed with a hole d' , through which 10 projects the tail of the safety sear F . The construction and arrangement of these parts is set forth fully in the specification of our aforesaid British Patent No. 165,857.

E is the aforesaid stop-piece and E' is a 15 part on the crank for coming against the said stop-piece at the end of the movement of the crank during recoil of the barrel, the said stop-piece E and the part E' being disposed equally on each side of a vertical plane 20 containing the axis of the barrel. E^2 is a barrel returning spring which is employed in addition to the usual fusee spring. The roller A^4 , with which the tail A^{3x} of the crank handle A^3 25 operates at the commencement of the recoil movement of the barrel as is well understood, has between it and its spindle or spigot A^{4x} a bush a of fibre or other material suitable for absorbing part of the 30 shock. This arrangement of the parts E , E' , and a is set forth fully in the specification of our aforesaid British Patent No. 165858.

The tumbler C is adapted to co-operate 35 with a projection B'^x on the firing pin B' for cocking the latter and to be moved out of the path of this projection (when the cocking operation has been completed) by a spring B^x which also operates upon the aforesaid actuating arm C^2 of the sear C' 40 so as to urge the latter into engagement with its bent on the firing pin. This arrangement is substantially the same as that described in the specification of our aforesaid British Patent No. 141605.

45 What we claim and desire to secure by Letters Patent of the United States is:—

1. In a machine gun of the barrel recoiling type, the combination with a part recoiling with the barrel, a crank pivoted on said 50 part, the lock, and a connecting rod connecting said crank to said lock of a centrally arranged and rigid stop-piece, a mass of metal on said crank, which mass strikes the stop-piece at the end of its movement during recoil of the barrel, and a device common to 55 the side lever axis pin and the firing spring for retaining these two parts in their assembled position.

2. In a machine gun of the barrel recoiling type, the combination with a part recoiling with the barrel, a crank pivoted on said part, the lock, and a connecting rod connecting said crank to said lock of a centrally arranged and rigid stop-piece, a mass of metal on said crank, which mass strikes 60 the stop-piece at the end of the movement 65

of said crank during recoil of the barrel, and a device operated upon by said spring to retain said axis pin in its assembled position.

3. In a machine gun of the barrel recoiling type, the combination with a part recoiling with the barrel, a crank pivoted on said part, the lock, and a connecting rod connecting said crank to said lock of a centrally arranged and rigid stop-piece which said crank strikes at the end of its movement during recoil of the barrel, a device common to the side lever axis pin and the firing spring for retaining these two parts in their assembled position, a cocking tumbler bearing loosely against part of the firing pin for cocking, a spring for moving the tumbler out of the path of said part after cocking and a sear engaging with said firing pin.

4. In a machine gun of the barrel recoiling type, the combination with a part recoiling with the barrel, a crank pivoted on said part, the lock, and a connecting rod connecting said crank to said lock of a centrally arranged and rigid stop-piece, a mass of metal on said crank, which mass strikes the stop-piece at the end of the movement of said crank during recoil of the barrel, a device operated upon by said spring to retain said axis pin in its assembled position, a cocking tumbler bearing loosely against part of the firing pin for cocking, a spring for moving the tumbler out of the path of said part after cocking and a sear engaging with said firing pin, said spring also serving normally to hold the sear in engagement with said firing pin.

5. In a machine gun of the barrel recoiling type, the combination with a part recoiling with the barrel, a crank pivoted on said part,

the lock, and a connecting rod connecting said crank to said lock, a handle connected to said crank, a roller with which a tail on said handle co-operates at the commencement of the recoil movement of the barrel, a spindle on which said roller is mounted, a bush of resilient material interposed between said roller and said spindle, a centrally arranged and rigid stop-piece, a mass of metal on said crank, which mass strikes the stop-piece at the end of the movement of said crank during recoil of the barrel, a device operated upon by said spring to retain said axis pin in its assembled position, a cocking tumbler bearing loosely against part of the firing pin for cocking, a spring for moving the tumbler out of the path of said part after cocking and a sear engaging with said firing pin, said spring also serving normally to hold the sear in engagement with said firing pin.

In testimony whereof we affix our signatures.

ARTHUR TREVOR DAWSON.
GEORGE THOMAS BUCKHAM.
